WALL PLAQUE

Albert W. Eddy, R.F.D. 1, Winona, Minn. 55987

Filed Oct. 13, 1965, Ser. No. 87,458

Term of patent 7 years

(Cl. D29—23)

FIG. 1.

FIG. 2.

FIG. 3.

FIG. 1 is a front view of the wall plaque showing my new design;

FIG. 2 is a right side view of the wall plaque, and

FIG. 3 is a bottom view of the wall plaque.

The back of the plaque is plain and unornamented.

I claim:

The ornamental design for a wall plaque, as shown and described.
